United States Patent [19]

Freehauf

[11] Patent Number: Des. 315,720

[45] Date of Patent: ** Mar. 26, 1991

[54] INJECTOR/EJECTOR LEVER FOR RACK
MOUNTED PLUG-IN CIRCUIT BOARD
MODULES

[75] Inventor: Eguene G. Freehauf, Ontario, Calif.

[73] Assignee: Canoga Industries, Inc., San Diego,
Calif.

[**] Term: 14 Years

[21] Appl. No.: 429,350

[22] Filed: Oct. 31, 1989

[57] CLAIM

The ornamental design for an injector/ejector lever for rack mounted, plug-in circuit board modules, as shown and described.

DESCRIPTION

FIG. 1 is a perspective view of an injector/ejector lever for rack mounted, plug-in circuit board modules showing my new design;

FIG. 2 is a front elevational view thereof;

FIG. 3 is a left side elevational view thereof, the right side elevational view being a mirror image;

FIG. 4 is a back elevational view thereof;

FIG. 5 is a top plan view thereof;

FIG. 6 is a bottom plan view thereof; and,

FIG. 7 is a left side elevational view of an injector/ejector lever for rack mounted, plug-in circuit board modules showing a second embodiment of my new design, the right side elevational view being a mirror image. The only difference between the first and second embodiments is the size and configuration of the radius at the top edge. The broken line showing is included for the purpose of illustrating environmental elements only and forms no part of the claimed design.

FIG. 1

FIG. 2

FIG. 3

FIG. 4

FIG. 5

FIG. 6

FIG. 7
